UNITED STATES PATENT OFFICE

HYMAN SLUTZKER, OF NEW YORK, N. Y.

CAP

Application filed May 21, 1929. Serial No. 364,757.

My invention relates to a new and improved cap.

One of the objects of my invention is to make an improved uniform cap having an adjustable stiffening device so that due allowance can be made for the shrinkage of the cap after it is washed.

Another object of my invention is to provide a cap having an improved adjustable and releasable device which serves as a shape or form, to stiffen the cap at the proper place and to give it the desired ornamental appearance.

Other objects of the invention are set forth in the following description and drawings which illustrate a preferred embodiment thereof, it being understood that the above statement of the objects of my invention is intended to generally explain the same and not to limit it in any manner.

Fig. 1 is a vertical central section partially in elevation.

Fig. 2 is a sectional view on the line 2—2 of Fig. 3.

Fig. 3 is a top view of the adjustable frame which serves to stiffen the cap and give it the desired shape.

Fig. 4 is a sectional view on the line 4—4 of Fig. 3.

Fig. 5 is a sectional view showing a different embodiment.

Fig. 6 is a top view of the frame utilized in the device shown in Fig. 5.

Fig. 7 is a sectional view on the line 7—7 of Fig. 6.

Fig. 8 is a sectional view on the line 8—8 of Fig. 6.

Fig. 9 is a side elevation showing the ends of the adjustable frame before they are connected to each other.

Fig. 10 is a view similar to Fig. 9 showing the ends of the frame after they have been connected to each other.

Fig. 11 is a top view of the frame when its ends are connected, as shown in Fig. 10.

It has heretofore been customary to provide caps of many types, and particularly uniform caps with interior frames or stiffening devices to maintain the cap in the desired 50 shape. Such frames were not easy to remove

when the caps were washed. In addition, the caps would shrink after they were washed, thus making it difficult to reinsert the frame.

According to my invention, an improved adjustable frame is provided which can be 55 readily removed and replaced, and which maintains the cap in the desired ornamental appearance.

The visor V is connected in the usual manner to a rim 1 which is made of any suitable 60 stiffened material and which may be provided with a sweat band. The top part of the cap is made of any suitable cloth or other material, said material being relatively soft

and yieldable so that it requires an inner 65 frame to hold it in the position shown in Fig. 1. The frame F comprises a strip of light resilient bendable metal such as aluminum, or the like. One of the ends of said strip passes through the opposite end, being adjustably 70 interlocked as will be later more fully described. A front flap 3 is provided with a hem 4 at the top thereof, through which the frame strip passes so that the overlapping ends of

said frame strip can pass within said hem, as illustrated in Figs. 2 and 3, for example. The depending portion of the front flap 3 is located upon the outside of the rim 1 and a fastener 5 is provided which passes through suitable openings in the rim 1 so as to firmly 80 detachably connect the flap 3 to the rim 1.

The top portion of the cap conceals the fastener 5. The top of the flap 3 is also provided with a second and inwardly projecting 85 fastener 6 which passes through an eyelet in the adjacent end of the sweat strip 7 so as to firmly hold the same in position. The frame piece F may also be provided with a fastener 6a which can also detachably pass through one of the eyelets in the adjacent end of the sweat strip 7. The frame member F can also be provided with another piece of hemmed

material 3a which is slidably mounted 90 thereon.

In the embodiment shown in Fig. 5, the front flap 3b which generally corresponds to the flap 3 shown in Fig. 3, is shorter than said flap 3, so that it merely serves to hold the adjacent end of the sweat strip 7. Like- 100

wise, in this embodiment the member 3a is omitted.

As shown in Fig. 9, one end of the frame piece F is provided with a slot 10 having arrow-shaped enlargements 11. The other end of the frame piece F is provided with notches 12 so as to produce projections 14, which may be of different width. If the left hand end of the device shown in Fig. 9 is laterally twisted, it can be readily inserted through the slot 10. Upon permitting the left hand end to turn until it is parallel to the right hand end, the said ends of the frame piece F are caused to engage at the broad ends of the enlargements 11, as shown in Fig. 10. The strip 3a shown in Fig. 3 provides a convenient hand-hold when it is desired to pull the frame out of the cap.

As shown in Fig. 4, the front flap 3 may have three layers of material in order to strengthen the same.

It will be noted that the front sweat strip or flap 3 is made of pliable material so that a hem can be formed therein by means of stitching.

I have shown a preferred embodiment of my invention, but it is clear that numerous changes and omissions can be made without departing from its spirit.

I claim:

1. A cap provided with a bottom rim, a top part fitting over said rim, an adjustable frame having overlapping ends located in said top part, said frame having a flexible flap member slidably mounted thereon, said flap member having its bottom portion located between said rim and the adjacent part of the top of said cap, and fastening means connecting the bottom portion of said flap member to said rim.
2. A cap having a resilient frame in the top thereof, a depending sweat strip mounted upon said frame, and a top sweat strip detachably connected to said front sweat strip, said top sweat strip having its other end connected to the frame by a detachable fastening device, so that the top sweat strip can be removed from the frame without removing the frame from the cap.

In testimony whereof I affix my signature.

HYMAN SLUTZKER.
